FIG. 1.

FIG. 2.

George KATEB
INVENTOR

UNITED STATES PATENT OFFICE

96,389

DESIGN FOR A ROBE

George Kateb, New York, N. Y.

Application June 27, 1935, Serial No. 57,422

Term of patent 3½ years

To all whom it may concern:

Be it known that I, George Kateb, a citizen of the United States of America, residing in Manhattan, county of New York, and State of New York, have invented a new, original, and ornamental Design for a Robe, of which the following is a specification, reference being had to the accompanying drawing, forming part thereof, wherein,

The circular parallel lines on the bottom of the cuff and skirt portions of the robe, represent cording.

I claim:

The ornamental design for a robe, substantially as shown and described.

GEORGE KATEB.
